UNITED STATES PATENT OFFICE

2,436,704

FLUID STREAM VACUUM PUMP

John William Tills, Upton, England

Application April 12, 1945, Serial No. 587,869
In Great Britain April 18, 1944

19 Claims. (Cl. 230—101)

1

This invention relates to fluid stream vacuum pumps.

One object is to increase pumping speed.

Another object is to provide a pump which will operate against relatively high forevacuum pressures.

A further object is to provide a pump which is suitable for pumping off large volumes of vapour of hydrocarbon solvents such as benzol.

A still further object is the provision of a pump of robust and durable construction especially suitable for many industrial processes.

These and other objects will become apparent from a perusal of the following description and the drawing annexed hereunto.

In the drawing: Fig. 1 is a side elevation, partially broken out and in section, showing a vessel and ancillary parts for working fluid supply and storage; Fig. 2 is a horizontal section on the line 11—11 of Fig. 1; Fig. 3 is a vertical fragmentary detail section, partly in elevation, showing the construction of a fluid stream pump in its relation to the vessel and other parts shown in Figs. 1 and 2; Fig. 4 is a general arrangement in side elevation showing one form of apparatus complete with backing pump; Fig. 5 is a general arrangement in side elevation, partially broken out and in section, showing another form of apparatus connected to a vessel to be evacuated and to a backing pump; Fig. 6 is a medial vertical section of one form of vapour stream nozzle and boiler unit; especially suitable for use at the lowest pressure stage of a cascade fluid stream pump; Fig. 7 is a medial section corresponding to Fig. 6; Fig. 8 is a medial section of one form of vapour stream nozzle and boiler unit especially suitable for use at an intermediate pressure stage of a cascade fluid stream pump; Fig. 9 is a medial section of one form of liquid discharge nozzle especially suitable for use at the highest pressure stage of a cascade fluid stream pump; Fig. 10 is a wiring diagram.

Referring more especially to Figs. 1 and 2, a substantially gas-tight steel vessel 10 has a lid 11 gas-tightly secured thereto. An electric motor 12 mounted on lid 11 drives, by way of a belt 13, a spindle 14 of a stuffing box assembly secured to the wall of vessel 10 so as to partially project therethrough. Spindle 14 is connected through a coupling 15, preferably flexible, to a multicylinder piston pump 16.

Pump 16 is fed by an inlet pipe 17 and discharges through a pipe 18 to a blow-off or pressure release valve assembly 19 supported, from the wall of vessel 10 and having an adjustment

2

spindle 20 passing through a stuffing box to atmosphere and terminating in a handwheel 21.

A pipe 22 extends between valve assembly 19 and a flange 23 to which it is secured by welding or brazing. Flange 23 is bolted or otherwise secured to the inner face of a pad 24 built into and extending through a wall of vessel 10. A flange 25, to which is attached one end of a pipe 26, is secured to the outside of pad 24. Pipe 26 (Fig. 3) is connectable to a liquid pressure indicator 28 by way of a valve 27. A pipe 29 is connectable to a branch of pipe 26 by way of a valve 30.

Pipe 29 leads from valve 30 to an outer wall 31 of a cooling jacket surrounding a cone-shaped body 32 of a fluid stream pump.

Lid 11 supports a transformer having a primary winding 36 energisable from the electric supply main and a low voltage (4 to 20 volts, by way of example) secondary winding 37. A centre tap of the secondary winding is grounded to the vessel and thence to the pump body 32.

A mechanical backing pump 38 (Fig. 4), driven by an electric motor 39, has its inlet connected by way of a forevacuum conduit 40 to a forevacuum enclosure formed above the level of liquid contained in vessel 10, within said vessel. The pump body 32 has at its smaller diameter end an inwardly projecting portion of a forevacuum conduit 70 bolted to and supported from a pad 71 on the lid 11.

A pipe 72 extends from the lowermost point at the forevacuum (small diameter) end of the pump body, by way of a valve 73 to a gas-tight collection vessel 74 having a draw-off valve 75.

A manifold 76 connected to the outer wall 31 at a point near the greatest diameter thereof provides communication between the cooling jacket around body 32 and three pipes 77, 78 and 79 by way of control valves 80, 81 and 82 respectively.

A high vacuum connection 130 extends as a side arm from the large diameter cylindrical end portion of the pump body 32 and terminates in a flange to which a flanged high vacuum conduit 131 may be secured.

An end plate 83 secured by bolts or other means (not shown) to the large diameter end of the pump body 32 by way of a flange 84 welded to said end.

Pipes 77, 78 and 79 extend through bores in plate 83 into the interior of body 32 and supply, respectively a low pressure nozzle and boiler unit (Figs. 6 and 7), a medium pressure nozzle and boiler unit (Fig. 8), and a high pressure nozzle

(Fig. 9) suitably supported within the interior of body 32.

Referring to Figs. 6 and 7, a low pressure nozzle and boiler unit is shown supported by a clip 85 from a base plate 86. The unit proper is constituted by a boiler case 87 of generally cylindrical shape having one end closed by a disc portion 88 and the other outwardly flared in a conical position 89. An electrical conductor, preferably copper strap may be conductively attached or united to valve block 95, by way of a lug 102.

A flash boiler is formed from a helically wound conduit 90 which may be of stainless steel. One end of conduit 90 is brazed into a connection 91 extending through a bore in end 88, secured thereto by a nut 92 engaging on a threaded portion of the connection shank; and insulated by sets of mica washers 93 and 94.

The other end of conduit 90 is brazed into a valve block 95, likewise insulatedly mounted from and extending through end 88. The valve block 95 is internally threaded at its outer end and receives a threaded portion 96 of a piston valve having a cylindrical portion 97 slidable in the last mentioned end portion of conduit 90. The valve can be adjusted by application of a screwdriver to a slot 98 whereby the cylindrical portion 97 is movable longitudinally of the end portion of conduit 90 to vary the effective area of a port presented by a bore 99 in said conduit.

A deflector 100 is coaxially supported with respect to the case 87 by a rod 101 brazed to end 88.

Referring to Fig. 8, a medium pressure nozzle and boiler unit includes a helical conduit 103 forming a flash boiler and a vapour discharge nozzle assembly. Said assembly comprises a nozzle block 104 having a conical bore 105 at one end coaxial with a counterbore 106 of an axial bore 107. Disposed around and parallel with bore 107 is a plurality of small bores 108.

A conical deflector 109, adapted to co-operate with the surface presented by bore 105 to provide a suitable path for vapour, has a cylindrical shank portion 110. Portion 110 is a sliding fit in axial bore 108 and is longitudinally adjustable therein by engagement of a tapped bore in its end with the shank of a set screw 111 to which the head is brazed to the end of block 104.

Block 104 has a threaded shank portion 112 engageable in a socket 113. One end of conduit 103 passes through a radial bore in the socket 113 and is attached to the socket by brazing. A screwed plug 114 is engaged in a tapped bore in the socket.

An electrical conductor, such as copper strap may be connected to the outside of block 104 by a lug 115.

The opposite end of conduit 103 passes into a socket 116 through a radial bore therein, and is secured to the socket by brazing.

Referring to Fig. 9 a liquid discharge nozzle may be formed on generally similar lines to the nozzle assembly of Fig. 8 with the exception that a pipe 117 is secured directly in the end of the socket 113.

Referring again to Fig. 3, the end plate 84 carries insulatedly two terminals 118 and 119 extending therethrough and connected respectively by suitably insulated, preferably braided or other semiflexible conductors 120 and 121 to lugs 102 and 115 on the low pressure nozzle and boiler unit and the medium pressure nozzle and boiler unit respectively.

The ends of the secondary winding 37 of the

transformer are brought out to two insulatedly mounted terminals 122 and 123 on lid 11.

One suitable electrical arrangement is shown diagrammatically in Fig. 10.

5 A variable reactor 124, is connected, in series with a switch 125 between terminal 122 on lid 11 and terminal 118 on plate 83, for control of heating current to the low pressure flash boiler. Likewise a second variable reactor 126 is connected in series with a switch 127 between terminal 123 on lid 11 and terminal 119 on plate 83, for control of heating current to the medium pressure flash boiler.

15 In operation, a working fluid, such as dibutyl phthalate, is introduced into vessel 10 so as to cover the coils 36 and 37 of the transformer.

The backing pump 38 is started up and after a suitable forevacuum has been attained within vessel 10 and pump body 32, pump 16 is started up. Valve 19 may be adjusted until, with valves 20 27 and 30 open, a desired liquid pressure obtains in pipe 29 as indicated in gauge 28. 15 to 50 lbs./sq. inch is a convenient range from which to select a working pressure.

25 Valves 80, 81 and 82 may be set so that under known pressure liquid flows through pipes 77, 78 and 79.

Finally the primary winding of the transformer is energised, causing heavy secondary currents to 30 flow through conduits 90 and 103 when switches 118, 119 and/or other control means are set to complete the respective secondary circuits.

In some instances the working fluid may be found to crack excessively after having exerted 35 pumping action with the pump body. For working under these conditions valve 73 is opened (vessel 74 being evacuated) and used working fluid is collected in vessel 74. It can be drawn off, for less exacting uses, after shut down of 40 the apparatus and breaking of the vacuum within vessel 74. The level in vessel 10 may be maintained by supply from an evacuated reservoir by way of a float valve (not shown) if desired.

If little or no cracking is encountered it may 45 be preferable to keep valve 73 closed and to recirculate the working fluid, used working fluid returning to tank 10 through conduit 70 under the influence of gravity.

Referring to Fig. 5, there is shown a form of 50 apparatus especially suitable for exhausting relatively large vessels which may be remotely disposed from a backing pump.

A vessel 132, such as an impregnator, has a 55 downwardly inclined vacuum connection 133, to which is attached a conduit length 134 of similar diameter. Disposed within conduit length 134 is a nozzle and flash boiler unit 135, which may be constructed for example in the manner shown in Figs. 6 and 7. The unit 135 is supported from 60 a plate 86 bolted to a pad 136 surrounding an opening in the lower part of the conduit wall.

Other conduit lengths 137 and 138, of progressively smaller diameter may each have nozzle and boiler units, constructed for example in the manner shown in Figs. 6 and 7.

The last conduit length is connected to a backing pump 139 by a forevacuum conduit 140 and has a relatively large diameter depending branch 141 to which a working fluid return pipe 142 is 70 connected.

Liquid working fluid under pressure, as described herein before is supplied from an assembly 143 including a transformer and liquid supply pump. Current to the flash boilers may be controlled in any suitable manner, such as

by independent variable reactors. In Fig. 10 all the boilers are shown as being connected in parallel to one end of a secondary winding of which the opposite end is grounded.

I claim:

1. In a fluid stream vacuum pump employing as working fluid an organic liquid having at room temperature a relatively low vapour pressure; nozzle means adapted to emit a stream of vapourised working fluid boiler means arranged to supply vapourised working fluid to said nozzle means; and means to supply liquid working fluid to said boiler means at a pressure of at least 15 lbs./sq. inch.

2. A fluid stream vacuum pump comprising a pump body having a high vacuum connection and a fore-vacuum connection respectively adjacent its opposite ends, a low pressure nozzle arranged within said body and directed towards the fore-vacuum end thereof, a high pressure nozzle arranged within said body between said low pressure nozzle and the fore-vacuum end of the pump body and directed towards said fore-vacuum end, means to supply vapourised working fluid to said low pressure nozzle, and means to supply working fluid in liquid phase to said high pressure nozzle.

3. A fluid stream vacuum pump comprising a conical pump body having a high vacuum connection and a fore-vacuum connection adjacent its larger and smaller ends respectively, a low pressure nozzle arranged within said body and directed towards said smaller end, a high pressure nozzle arranged within said body between said low pressure nozzle and said smaller end and directed towards said smaller end, means to supply vapourised working fluid to said low pressure nozzle, and means to supply working fluid in liquid phase to said high pressure nozzle.

4. A fluid stream vacuum pump comprising an enclosed storage means for working fluid, a conical pump body having a high vacuum connection and a fore-vacuum adjacent its larger and smaller ends respectively, a low pressure nozzle arranged within said body and directed towards said smaller end, a high pressure nozzle arranged within said body between said low pressure nozzle and said smaller end, and directed towards said smaller end, boiler means to vapourise working fluid and adapted to supply vapourised working fluid to said low pressure nozzle, and means to supply working fluid in liquid phase from said storage means to said boiler means and to said high pressure nozzle.

5. A fluid stream vacuum pump comprising an enclosed storage means for working fluid, a conical pump body having a high vacuum connection and a fore-vacuum connection adjacent its larger and smaller ends respectively, a low pressure nozzle arranged within said body and directed towards said smaller end, a high pressure nozzle arranged within said body between said low pressure nozzle and said smaller end and directed towards said smaller end, boiler means to vapourise working fluid and adapted to supply vapourised working fluid to said low pressure nozzle, and means to supply working fluid in liquid phase under pressure from said storage means to said boiler means and to said high pressure nozzle.

6. A fluid stream vacuum pump comprising an enclosed storage means for working fluid, a conical pump body having a high vacuum connection and a fore-vacuum connection adjacent its larger and smaller ends respectively, a low pres-

sure nozzle arranged within said body and directed towards said smaller end, a high pressure nozzle arranged within said body between said low pressure nozzle and said smaller end and directed towards said smaller end, a flash boiler arranged within said body and adapted to supply vapourised working fluid to said low pressure nozzle, and means to supply working fluid in liquid phase under pressure from said storage means to said flash boiler and to said high pressure nozzle.

7. A fluid stream vacuum pump comprising an enclosed storage means for working fluid, a conical pump body having a high vacuum connection and a fore-vacuum connection adjacent its larger and smaller ends respectively, an enclosed cooling jacket having an inlet and an outlet and disposed around said body, a low pressure nozzle arranged within said body and directed towards said smaller end, a high pressure nozzle arranged within said body between said low pressure nozzle and said smaller end and directed towards said smaller end, boiler means to vapourise working fluid and adapted to supply vapourised working fluid to said low pressure nozzle, means to supply working fluid in liquid phase under pressure from said storage means to said jacket inlet, and conduit means between said jacket outlet and said boiler means and to said high pressure nozzle.

8. A fluid stream vacuum pump comprising an enclosed storage means for working fluid, a conical pump body having a high vacuum connection and a fore-vacuum connection adjacent its larger and smaller ends respectively, a low pressure nozzle arranged within said body and directed towards said smaller end, an intermediate pressure nozzle arranged within said body between said low pressure nozzle and said smaller end and directed towards said smaller end, a high pressure nozzle arranged within said body between said intermediate pressure nozzle and said smaller end and directed towards said smaller end, boiler means adapted to supply vapourised working fluid to said low pressure and intermediate pressure nozzles, and means to supply working fluid in liquid phase under pressure from said storage means to said boiler means and to said high pressure nozzle.

9. A fluid stream vacuum pump comprising an enclosed storage means for working fluid, a conical pump body having a high vacuum connection and a fore-vacuum connection adjacent its larger and smaller ends respectively, a low pressure nozzle arranged within said body and directed towards said smaller end, an intermediate pressure nozzle arranged within said body between said low pressure nozzle and said smaller end and directed towards said smaller end, a high pressure nozzle arranged within said body between said intermediate pressure nozzle and said smaller end and directed towards said smaller end, a flash boiler within said body adapted to supply vapourised working fluid to said low pressure nozzle, a second flash boiler within said body adapted to supply vapourised working fluid to said intermediate pressure nozzle, and means to supply working fluid in liquid phase under pressure from said storage means to said boilers and to said high pressure nozzle.

10. A fluid stream vacuum pump comprising an enclosed storage means for working fluid, a conical pump body having a high vacuum connection and a fore-vacuum connection adjacent its larger and smaller ends respectively, a low pressure nozzle arranged within said body and

directed towards said smaller end, an intermediate pressure nozzle arranged within said body between said low pressure nozzle and said smaller end and directed towards said smaller end, a high pressure nozzle arranged within said body between said intermediate pressure nozzle and said smaller end and directed towards said smaller end, boiler means adapted to supply vapourised working fluid to said low pressure and intermediate pressure nozzles, means to supply working fluid in liquid phase under pressure from said storage means to said boiler means and to said high pressure nozzle, and means to return condensate and used working fluid back to said storage means.

11. In a fluid stream vacuum pump employing as working fluid an organic liquid having at room temperature a relatively low vapour pressure, a liquid jacketed body, nozzle means to discharge a stream of working fluid within said body for effecting pumping action, working fluid storage means, and means for supplying working fluid to said nozzle means by way of the liquid jacket.

12. In a fluid stream vacuum pump, a liquid jacketed body, nozzle means to discharge a stream of working fluid within said body for effecting pumping action, working fluid storage means, and means for supplying working fluid to said nozzle means under a pressure of at least 15 lbs./sq. inch by way of the liquid jacket.

13. In a vapour stream vacuum pump employing as working fluid an organic liquid having at room temperature a relatively low vapour pressure, a body having a liquid jacket, nozzle means adapted to emit a stream of vapourised working fluid within said body for effecting pumping action, working fluid storage means, and means for supplying working fluid to said nozzle means by way of the liquid jacket.

14. An arrangement for evacuating a vessel, comprising a high vacuum connection on said vessel, a backing pump, a plurality of conduit lengths of progressively smaller bore extending between said high vacuum connection and said backing pump and sloping downwards towards said backing pump, nozzle means disposed within each conduit length and directed away from said high vacuum connection, working fluid storage means, means for supplying working fluid to said nozzle means, and means for returning working fluid discharged through said nozzle means to said storage means.

15. In a fluid stream vacuum pump employing as working fluid an organic liquid having at room temperature a relatively low vapour pressure, unitary flash boiler and nozzle means; and means to supply working fluid to said unitary flash boiler and nozzle means at a pressure of at least fifteen pounds per square inch absolute.

16. In a fluid stream vacuum pump employing as working fluid an organic liquid having at room temperature a relatively low vapour pressure; boiler means constituted by an electrically

conductive tube arranged to supply vapourized working fluid to said nozzle means; means to pass an electrical current of high amperage through said tube to effect heating thereof; and means to supply working fluid to said boiler means at a pressure of at least fifteen pounds per square inch absolute.

17. A fluid stream vacuum pump comprising a pump body having a high vacuum connection and a fore-vacuum connection respectively adjacent its opposite ends, a low pressure nozzle arranged within said body and directed towards the fore-vacuum end thereof, a high pressure nozzle arranged within said body between said low pressure nozzle and the fore-vacuum end of the body and directed towards said fore-vacuum end, means to supply vapourized working fluid to said low pressure nozzle at a pressure of at least fifteen pounds per square inch absolute, and means to supply working fluid in liquid phase to said high pressure nozzle at a pressure of at least fifteen pounds per square inch absolute.

18. An arrangement for evacuating a vessel, comprising a high vacuum connection on said vessel, a backing pump, a conduit length extending between said backing pump and said high vacuum connection and sloping downwards towards said backing pump, a unitary flash boiler and nozzle disposed within said conduit length and directed away from said high vacuum connection, working fluid storage means, means for supplying working fluid on liquid phase at a pressure of at least fifteen pounds per square inch absolute to said unitary boiler and nozzle, and means for returning working fluid discharged through the nozzle to said storage means.

19. An arrangement for evacuating a vessel, comprising a high vacuum connection on said vessel, a backing pump, a plurality of conduit lengths of progressively smaller bore extending between said high vacuum connection and said backing pump and sloping downwards towards said backing pump, nozzle means disposed within each conduit length and directed away from said high vacuum connection, working fluid storage means, means for supplying working fluid at a pressure of at least fifteen pounds per square inch in absolute to said nozzle means, and means for returning working fluid discharged through said nozzle means to said storage means.
